UNITED STATES PATENT OFFICE.

JOHN A. KNOTTS AND WILLIAM R. McNEICE, OF CANEY, KANSAS.

OIL OR WATER PUMP.

Application filed February 10, 1921. Serial No. 444,060.

To all whom it may concern:

Be it known that we, JOHN A. KNOTTS and WILLIAM R. McNEICE, citizens of the United States, residing at Caney, in the county of 5 Montgomery, State of Kansas, have invented a new and useful Oil or Water Pump, of which the following is a specification.

This invention relates to pump constructions, and more particularly to pumps employed in connection with oil wells or the like.

The primary object of the invention is to provide means for operating the ball valves of the pump construction, to mechanically 15 unseat the same, thereby permitting the sediment or other foreign matter which may collect under the ball valve, to be washed from the seat thereof.

A further object of the invention is to 20 provide a means for releasing the oil contained in the pump, when the tubing is being pulled, thereby eliminating any possibility of oil being removed during the pulling operation.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

35 Referring to the drawing:—

Figure 1 illustrates a longitudinal sectional view through a device constructed in accordance with the present invention.

Figure 2 illustrates a longitudinal sectional view through another portion of the device, the same being a continuation of the device shown in Figure 1, and

40 Figure 3 illustrates a sectional view through the lower portion of the device closing the arm for actuating the ball valve.

Referring to the drawing in detail, the reference character 5 designates the working barrel or pump tube in which the pump rod indicated by the reference character 6 45 operates, the pump rod being of a particular construction employed in pumping oil wells, the same being provided with working valves as shown by the reference character 7.

This pump rod extends through the casting 8, the lower extremity thereof being threaded as at 9 and positioned in the

threaded opening of the housing 10, there being provided a circumferential shoulder indicated at 11 and formed integral with the threaded portion 9, for purposes to be 60 hereinafter more fully described.

Positioned within the pump barrel at the lower extremity thereof, is the standing valve cage 12, which includes an upper section 13 and a lower section 14, the lower section having a threaded connection with the upper section 12, as at 15, suitable washers 16 being provided to prevent the fluid from passing between the valve cage, and inner 65 surface of the pump barrel.

As shown, the upper portion 12 of the standing valve cage is cut away to provide the valve chamber 17 adapted to accommodate the ball valve 19, which is normally seated on the valve seat 20 in a manner to 70 release the gases and air within the pump barrel, but prevent the fluid from running back into the well.

The upper portion of the upper section 12 is reduced as at 21 to accommodate the movable ring 22, which ring is held on the reduced portion as by means of the threaded ring 23, which cooperates with threads provided on the extreme upper end of the upper section so that the ring member 22 may 75 be moved throughout the length of the reduced portion, the ring contacting with the lower edge of the ring 23, on its upward movement, and contacting with the shoulders 24 when the same has reached the limit 80 of its downward movement.

Secured to the ring 22, at its upper end, is an operating arm 25, which has its lower end curved inwardly as at 26, and flattened as at 27, so that the same will ride over the 85 surface of the ball valve 19, and seat under the ball valve so that upward movement of the ring 22 will move the ball valve from its seat, and permit the fluid supported by the ball valve to flow back into the well, and 90 carry therewith, any sediment which may collect between the ball valve 19 and its seat.

The lower extremity of the pump rod is also tapered as at 28, to conform to the tapered threaded opening 29 of the standing valve cage, so that the rod may be dropped into engagement with the valve cage, the lower edges of the housing 10 contacting with the ring 22 to cause the same to move 95 downwardly accomplishing the unseating of 100 valve 19.

If it is desired to remove the standing

valve cage, it is only necessary to position the tapered threaded portion 28 of the rod in the opening 29, whereupon the ball valve 19 is unseated to permit the fluid to flow back into the well. The pump rod may now be used to extract the standing valve cage.

Upon replacing the standing valve cage, the same is positioned on the threaded portion 28 and inserted in the well, the rod is now rotated in a manner to disconnect the valve rod and standing valve cage, the coiled spring 30, acting to return the ring 22 to its normal position, and consequently permitting the ball valve 19 to seat, to accomplish the pumping operation.

Having thus described the invention, what is claimed as new is:

In a device of the character described, a standing valve cage having a laterally disposed opening, a valve seat in the valve cage, 20 a ring member slidably mounted on the up-

per end of the valve cage, a coiled spring contacting with the ring member for normally urging the ring member to the limit of its upward movement, a spring arm carried by the ring member and having an inwardly extended end portion, said inwardly extended end portion adapted to extend through the openings and being flattened to engage a ball valve member seated on the valve seat, and said spring arm adapted to move to a position under the ball valve to hold the same out of engagement with the valve seat.

In testimony that we claim the foregoing as our own, we have hereto affixed our signatures in the presence of two witnesses.

JOHN A. KNOTTS.

WILLIAM R. McNEICE.
